UNITED STATES PATENT OFFICE.

FRANK M. FAHLOR, OF MANORVILLE, PENNSYLVANIA.

FEED GAUGE.

Application filed January 23, 1923. Serial No. 614,414.

To all whom it may concern:

Be it known that I, FRANK M. FAHLOR, a citizen of the United States, residing at Manorville, in the county of Armstrong and State of Pennsylvania, have invented new and useful Improvements in Feed Gauges, of which the following is a specification.

This invention relates to feed gauges, and more particularly to a feed gauge adapted for use in connection with platen printing presses.

One of the main objects of the invention is to provide a gauge device of simple construction and operation which may be readily applied to a platen and the tympan clamping bails therefor without necessitating any changes in construction of the platen or any material changes in the bails. A further object is to provide gauges which have a great range of adjustment and which occupy but little space. Further objects will appear from the detailed description.

In the drawings:—

Figure 1 is a plan view of the gauges as applied;

Figure 2 is a side view;

Figures 3, 4, and 5 are sections taken substantially on lines 3—3, 4—4, and 5—5, respectively, of Fig. 1;

Figure 6 is a detail of a modified form of gauge section;

Figure 7 is a plan view, partly in section, of a modified form of clamping and supporting frame;

Figure 8 is a modified form of side gauge;

Figure 9 is another modified form of gauge section;

Figure 10 is a section taken substantially on line 10—10 of Fig. 9.

The gauges are to be used in connection with a platen A of standard type provided with the usual backing or tympan B which is held tightly stretched over the platen and is securely clamped in position by bails

C of substantially elongated U-shape which are pivotally secured by rivets or screw pins c to the sides of platen A. The platen and parts associated therewith are of standard construction and form no part of my invention except in so far as they co-operate with means to be hereinafter described for supporting the gauges.

A supporting frame 1 of elongated U-shape fits about one of the bails C and is pivoted to the bail at opposite ends thereof, by means of pins 2, so as to be adjustable

about an axis extending longitudinally of the bail. Each arm 1^a of this frame is provided with an arcuate slot 3 disposed concentric with pin 2, this slot receiving a screw stud 4 secured in the arm of bail C. A wing nut 5 is threaded onto stud 4 and coacts with arm 1^a and the stud for securing frame 1 in adjustment about pins 2. The bight portion 1^b of frame 1 is provided with a longitudinally extending groove 1^c and with a rabbet 1^d for receiving gauge blocks 6 slidable on bight portion 1^b. Each of the blocks 6 is provided, in its upper face, with a transversely extending dovetail groove 7 which slidably receives a lower gauge section 8 the lateral edges of which are beveled to fit within groove 7. A screw stud 9 is secured in block 6 adjacent to groove 7 and receives a nut 10 which projects above lower gauge section 8 for securing the same in adjustment in block 6. Lower gauge section 8 is provided, in its underface, with a longitudinally extending groove which slidably receives an upper gauge section 11 provided with a screw stud 12 which projects through a slot 13 provided through section 8 for this purpose. A nut 14 is threaded on stud 12 for securing sections 11 and 8 in relative adjustment. This provides a telescoping gauge of very simple and efficient construction which has a great range of adjustment and can be quickly and accurately adjusted as desired.

Upper gauge section 11 is provided, at its upper end, with a transversely extending head 15 provided in its upper face with a groove 16. A plate 17 is secured to the upper face of head 15 and is provided with a downwardly curved resilient finger 18 which presses upon the upper face of a resilient tongue 19 which is inserted through groove 16 and is confined between finger 18 and upper gauge section 11 which cooperate to hold tongue 19 in adjustment. The bottom gauges indicated generally by 20 project a predetermined distance over the upper face of the platen, the heads 15 resting upon the backing or tympan B so as to form stops for limiting movement of a sheet of paper toward the bottom of the platen. The side gauges indicated generally by 21 is constructed similarly to bottom gauges 20 with the exception that head 15 and the parts associated therewith are directed at right angles to the heads 15 of bottom gauges 20. The side gauge 21 serves to limit

means for securing said sections in adjustment, upper gauge sections slidably mounted in the lower sections, said lower sections being provided with longitudinally extending slots, the upper gauge sections being provided with screw studs projecting through said slots, nuts threaded on said studs and contacting with the lower gauge sections for securing said lower and upper sections in adjustment, and stop members carried by the upper gauge sections at the upper ends thereof.

7. In a device of the character described, a frame of substantially elongated U-shape, blocks carried by said frame, lower gauge sections slideable transversely of the blocks, means for securing said sections in ad-

justment, upper gauge sections slidably mounted in the lower sections, said lower sections being provided with longitudinally extending slots, the upper gauge sections being provided with screw studs projecting through said slots, nuts threaded on said studs and contacting with the lower gauge sections for securing said lower and upper sections in adjustment, stop members carried by the upper gauge sections at the upper ends thereof, and index points carried by the upper sections and projecting through said slots, the lower gauge sections being graduated adjacent to the lateral edges of the slots.

In testimony whereof I affix my signature.
FRANK M. FAHLOR.
